UNITED STATES PATENT OFFICE.

HOWARD M. BARBER, OF STONINGTON, CONNECTICUT, ASSIGNOR TO C. B. COTRELL & SONS COMPANY, OF NEW YORK, N. Y., A CORPORATION OF DELAWARE.

SHEET-HANDLING MACHINE

1,385,067.

Specification of Letters Patent. Patented July 19, 1921.

Original application filed January 4, 1918, Serial No. 210,342. Divided and this application filed April 23, 1918. Serial No. 230,272.

To all whom it may concern:

Be it known that I, HOWARD M. BARBER, a citizen of the United States, and resident of Stonington, in the county of New London and State of Connecticut, have invented a new and useful Improvement in Sheet-Handling Machines, of which the following is a specification.

My invention relates to improvements in signature stitching and folding mechanisms whereby accurate folding of the signature along its stitched line is insured by means for adjusting the parts while the mechanisms are operating.

My invention more particularly includes a rotary sheet carrier such, for instance, as the cylinder forming part of a folding mechanism, grippers on the carrier, means for operating the grippers at their taking and releasing points, a stitcher mechanism, its table, a sheet stop for the stitcher table, a cam on the rotary sheet carrier arranged to operate the sheet stop to permit the stitched signature to be taken by the grippers on the rotary carrier at the proper time, and means for adjusting the position of the sheet stop with respect to the taking point of said grippers whereby the grippers will be caused to close onto the signature at varying distances from the head of the signature in the rotary movement of the carrier to accurately adjust the fold line to bring it along the stitched line of the signature, the whole being accomplished while the machine is in operation; it being understood that the stitcher mechanism is adjusted together with the sheet stop to maintain the predetermined distance between the sheet stop and the stitched line.

A practical embodiment of my invention is represented in the accompanying drawings in which—

Figure 1 represents in end elevation so much of a sheet handling machine as will give a clear understanding of my invention, the female folding cylinder being removed.

Fig. 2 is a section taken in the plane of the line II—II of Fig. 1, a portion of the female folding cylinder being shown.

Fig. 3 is a detail section at the sheet stop.

Fig. 4 is a cross section taken in the plane of the line IV—IV of Fig. 2, and

Fig. 5 is a detail section taken in the plane of the line V—V of Fig. 4.

The stitcher table is denoted by 1, the stitcher mechanism generally, by 2, and its driving shaft by 3, which stitcher may be of any well known or approved construction adapted to stitch a signature while the movement of the signature is arrested on the stitcher table. The signature may be fed onto the stitcher table by the endless tape carriers 4, 5.

The sheet stop for the stitcher table comprises a plurality of fingers 6 fixed to a cross bar 7, carried by arms 8, 9, depending from the cross shaft 10 supported in the side frames 11, 12 of the machine. The free ends of these stop fingers 6, when the stop is lowered, are located in the circumferential grooves 13 of the rotary sheet carrier 14, which, in the present instance, is one member of a pair of coacting folding cylinders, namely, the member which carries the folding blade 15 which coacts with the folding jaw 16 carried by the other member 17 of the folding cylinders. This rotary carrier 14 is mounted on a suitable cross shaft 18, and it carries a set of tumbler actuated grippers 19, the tumbler 20 of which grippers is engaged by its actuating pin 21 at the taking point for the grippers and by the actuating pin 22 at the releasing point for the grippers, this mechanism being of well known and approved form.

The mechanism for controlling the operation of the folding blade 15 and folding jaws 16, is not shown herein, but it is understood that it may be of any well known or approved construction operative to cause the signature to be folded off from the carrier 14 onto the carrier 17. The rotary carrier 14 is provided with a peripheral cam 23 arranged in position to engage a stud or roller 24 carried by a two-armed lever 25, 26, fixed to the cross bar 7 of the sheet stop, at the proper time to raise the sheet stop to permit the stitched signature to be transferred from the stitcher table 1 to the grippers 19. A rod 27 is attached at one end to the arm 26, 100

and slidably engages a stud 28. A spring 29 interposed between this stud 28 and a collar 30, tends to yieldingly hold the stop in its operative position with the fingers 6 in the 5 circumferential grooves 13 of the carrier 14.

The means which I provide for adjusting the fold line with respect to the stitched line of the signature is constructed, arranged and operated as follows:

10 The auxiliary frame 31 of the stitcher mechanism has fixed thereto, by suitable screws 32, a pair of studs 33 which extend into the main frame 34 of the stitcher mechanism.

15 Means for moving the auxiliary frame includes a cross shaft 35 having worms 36 meshing with worm gears 37 which have a threaded engagement with the studs 33. This shaft 35 is provided with a suitable 20 hand wheel 38, and by turning this hand wheel, the auxiliary frame is moved longitudinally of the table 1. The sheet stop is moved with the auxiliary frame of the stitcher to maintain the stitcher and sheet

25 stop in the same relationship. This is accomplished by providing upright shafts 39 which have a bevel gear engagement 40, 41, with the shaft 35, and a bevel gear engagement 42, 43, with the longitudinally ar-

30 ranged shafts 44 mounted adjacent to the carriers 43 in fixed bearings 45 and at their other ends having a screw threaded engagement with studs 46 at the free ends of the depending arms 8, 9.

35 In operation, the signature is fed onto the stitcher table 1, against the fingers 6 of the sheet stop, and the signatures are then stitched. The sheet stop fingers are then raised at the proper time to transfer the 40 head end of the signature to the grippers 19 of the rotary carrier 14. The grippers 19 close on the head end of the signature and at the proper time the grippers 19 are opened to release the signature to permit it 45 to be folded off onto the carrier 17 by the coaction of the folding devices 15, 16.

To accurately register the fold along the stitched line, the sheet stop and the stitcher 50 may be bodily adjusted along the stitcher table with respect to the taking point of the grippers 19, to cause the grippers to close onto the head end of the signature at vary-

ing distances from the head of the signature, as may be necessary for registry. This 55 may be readily accomplished as heretofore pointed out, by turning the hand wheel 38 in one direction or the other.

It is evident that various changes may be resorted to in the form, construction and arrangement of the several parts without departing from the spirit and scope of my invention, and hence I do not wish to limit myself to the construction herein shown and described, but

What I claim is:

1. A stitcher, its stationary table, a sheet stop and a common means connected to both the stitcher and sheet stop for adjusting their position and maintaining their predetermined distance from each other.

2. A stitcher, its stationary table, a sheet stop and means common to the stitcher and sheet stop for adjusting their position and maintaining their predetermined distance from each other while the parts are operating.

3. A stitcher, its table, a sheet stop, and means comprising a hand shaft connected to both the stitcher and sheet stop for adjusting their position, maintaining their predetermined distance from each other.

4. A stitcher, its table, a sheet stop, and means comprising a hand shaft connected to both the stitcher and sheet stop for adjusting their position, maintaining their predetermined distance from each other while the parts are operating.

5. A stitcher, its movable support, a sheet stop, its movable support, a stationary table and a common means connected to both the 90 stitcher and sheet stop supports for moving them and maintaining their predetermined distance from each other.

6. A stitcher, its movable support, a sheet stop, its movable support, a stationary table 95 and a common means connected to both the stitcher and sheet stop supports for moving them and maintaining their predetermined distance from each other while the parts are operating.

In testimony that I claim the foregoing as my invention, I have signed my name this sixteenth day of April, 1918.

HOWARD M. BARBER.
